END-ON ROD CUTTER

Roy C. Day, Crawfordsville, Ind.

Application October 21, 1938, Serial No. 236,175

4 Claims. (Cl. 30—95)

My invention relates to improvements in end-on rod cutters. It more especially includes the distinctive features recited in the claims.

The purpose of my invention is to provide a mechanism for severing the ends of rods which project from restricted recesses of concrete walls wherein the rods are usually used to retain the forms employed in the construction of such walls.

Having in mind this and analogous forms of my invention, I illustrate on the accompanying drawing such instances of adaptation as will show its broad underlying features as herein applied and suggestive of other associated expedients without limiting myself to the specific details shown thereon and described herein.

Fig. 1 is a side elevation in section showing the cutters in position against a rod which is to be cut off.

Fig. 2 is a front end elevation of Fig. 1 showing the jaws.

Fig. 3 is a front end elevation of the jaw holder showing the jaws removed.

Fig. 4 is a top plan view of a detached cutter holding jaw.

Fig. 5 is a front elevation of a conventionally known ratchet wrench.

Fig. 6 is an enlarged diagrammatic elevation showing jaws and cutters formed integrally with each other and positioned in the restricted space of a conical depression formed in the face of a concrete wall.

Without departing from the broad spirit of the invention in its actual application to the formation of concrete or similar walls, I may use whatever expedients that the varying exigencies of practice may demand in the employment of co-operating alternatives or structural equivalent.

In the formation of concrete walls, wooden form sidewalls are placed adjacent the space that is to be occupied by the proposed wall. Many rods are passed through both walls and on these rods against the inside face of the wall, cones are placed with their large ends against the form. They may be secured to external adjusting means which encircle the rods in any desired manner, which adjusting means are placed on the projecting ends of the rods on the outside of the form. These are used to bring the walls into alignment and hold them against displacement while the concrete is placed in the interspace.

After the concrete has set, the forms are removed, and the cones slid off from the ends of the rods. After the cones are removed a conical recess is left in the wall and the rods remain in the wall.

Sometimes these rods are removed entirely and the hole formed by them, as well as the conical recesses formed by the cones, is filled with cement, or at other times, the projecting ends of the rods are simply cut off flush with the outside faces of the wall and the conical recesses on both sides of the wall are filled with cement. In the use of this expedient, the ends of the rods being flush with the wall and the surrounding cement, they become rusted and will disfigure the wall face.

I overcome these defects, by cutting off the rod some distance in from the face of the wall, so that when the conical recess is filled with cement, the cut off ends of the rod will be completely covered, thus overcoming the disfigurement referred to.

To accomplish my purpose, I use a cylindrical member 1 that is of enlarged diameter at the front end 2, presenting a threaded portion 5 between such end and the smaller diameter 3. Adjacent the smaller diameter, a square end 4 is formed. A hole 6 is formed throughout the length of the member 1. This accommodates the projecting ends of rods 23.

A plurality of grooves 7 are formed lengthwise and externally of the body 1. About mid length of the grooves 7, projections 8 are formed in each groove. These projections serve as fulcrums for the cutter jaws 9. The jaws on the upper face are beveled at 12. The rear end of the jaws have an upward curve 10, and about midway of their length, a recess 11 is formed to receive the projection 8.

At the forward end of the jaws 9, removable cutters 13 pass through openings in the jaws where they are held by set screws 14.

The cutters are moved into engagement with a rod to produce severing grooves 19, through the rotation of a hand wheel 16 that moves endwise on the threads 5 and 18 until the bevel 17 engages the incline 12 on the outer face of the jaws. The cutters 13 are retracted from the rod 23 by reason of the threads 18 of the hand wheel 16 formed in its hub portion 15, engage the upturned ends 10 of the jaws, as the hand wheel is "backward," thus radially moving such ends toward the center of the rod and at the same time by reason of the fulcrum 8 moving the cutters radially away from the rod.

A conventional ratchet wrench shown in Fig. 5, is used to engage the square end 4 to rotate the body member 1. Each rotation of the member 1 with its attached jaws and cutters, will produce a groove of a certain depth in the rod. On the

completion of such a groove, the hand wheel 16 is moved slightly to the right, so as to engage the bevel 17 with the inclines 12. Thus the cutters 13 are moved into deeper engagement with the rod, after which the ratchet wrench 20 is again used on the square end 4 to carry the cutters entirely around the rod the second time, then the hand wheel is again operated and the process repeated until the rod is entirely or nearly separate. If just nearly separated, the projecting ends are easily broken off.

If desired, the hand wheel 16 may be substituted by any desired form of ratchet manipulation.

The jaws 9 may be substituted by jaws 21 shown in Fig. 6, with which the cutters are integrally formed. The front end of these jaws are beveled so as to enter the conical recess 22 to a greater distance than square ended jaws might permit.

My present invention must not be confused with conventional pipe cutters, because none of these devices can possibly be used to cut off a rod within a restricted recess as described above.

What I claim is:

1. In end-on rod cutters, a main member constituting the body having a rod opening throughout the length thereof, a plurality of external lengthwise grooves in such body, a projection constituting a fulcrum in each groove, an external threaded portion on the body of the member between its ends, threaded means external of the body member for movement endwise thereon, a beveled opening in said means, a plurality of lengthwise cutter jaws in the grooves each jaw being provided with a notch adapted to engage the fulcrum, cutter terminations of the jaws at

one end thereof, outwardly curving terminations at the other end of the jaws, inclined upper faces of the jaws, and means for rotating the body member to carry the cutters around the circumference of the rod.

2. In end-on rod cutters, a body member provided with a rod receiving opening throughout its length and external threads thereon, a plurality of radially adjustable positioned attachable and detachable cutter jaws carried loosely by the body member, a fulcrum for the jaws approximately midway of their length, means external of the body member comprising a hand operated internally threaded sleeve for moving the cutters radially inwardly and outwardly, and means for rotating the body member throughout 360 degrees and over.

3. In end-on rod cutters, a body member having a lengthwise rod receiving opening throughout its length, a plurality of cutter jaws, a plurality of grooves containing radial projections formed in the grooves of the body member adapted to receive the jaws while fulcrumed on the projection, means for radially moving the cutters in the grooves toward or from the rod, said jaws having beveled faces near their front ends and integrally formed cutters, and means for rotating the body member throughout more than 360 degrees to form a groove in the rod of increasing depths throughout its circumference.

4. In end-on rod cutters, a lengthwise jaw member having a curving upper face near the rear end and a beveled upper face near the front end, and a recess in its underside adapted to receive a fulcrum, and cutting means associated with the latter end of the jaw.

ROY C. DAY.
